UNITED STATES PATENT OFFICE.

BENJAMIN H. ERWIN, OF MISHAWAKA, INDIANA, ASSIGNOR TO THE INDESTRUCTO TRUNK COMPANY, A CORPORATION OF OHIO.

TRUNK LOCK.

Application filed October 27, 1926. Serial No. 144,450.

This invention relates to trunk locks and specifically to those locks which are actuated by movement of the hasp to draw the trunk sections together when locking the trunk and 5 separate them when unlocking it. Among other objects the invention aims to provide a trunk lock of this character which is particularly easy to operate and which is especially effective in drawing together and separating the trunk sections.

The invention may be understood by reference to one illustrative embodiment shown in the accompanying drawings, in which:

Fig. 1 is a fragmentary elevation showing a 15 portion of a trunk equipped with the improved lock;

Fig. 2 is a similar view looking from the opposite side of the trunk with parts broken away to illustrate the construction more 20 clearly;

Fig. 3 is a section on line 3—3 of Fig. 1;

Fig. 4 is a view similar to Fig. 3, but showing the edges of the trunk sections separated;

Fig. 5 is a section on line 5—5 of Fig. 1;

Fig. 6 is a similar view showing the parts in the position which they assume when the hasp has been moved about half way toward its locked position; and

Fig. 7 is a fragmentary view showing the 30 positions of the parts when the hasp is moved to its outermost position.

Referring to the drawings, and first to Figs. 1 and 2, there are shown portions of sections 35 10 and 11 of a trunk, for example, a wardrobe trunk, the meeting edges of which are reinforced by the usual metallic valances, one of which, the valance 12, is shown in Fig. 1. To guide the edges of the trunk during closing, the usual dowels 13 are provided. It will be 40 understood that to conserve space, only a portion of the trunk is shown and that therefore only one pair of dowels is included, but that in a commercial trunk several such pairs are ordinarily employed.

At any convenient point along one of the edges of the trunk a hasp 14 is pivotally connected to the trunk as at 15, so as to swing in a plane at right angles to the face of the trunk, and connect the two trunk sections together.

The hasp 14 carries a key controlled lock 16 50 near its outer end and said key controlled lock engages with an escutcheon plate 17 to lock the trunk when the hasp is swung into engagement with the escutcheon, as best shown in

Fig. 5. The parts so far described may be of conventional construction.

In order to effect locking and unlocking of the trunk by independent locking devices actuated upon swinging of the hasp 14, a rod 18 is carried by trunk section 10 parallel to the edge thereof and is connected with the hasp, by a linkage to be described, so that the rod may be rocked on its axis. The rod 18 is carried within loops 19 providing bearings for the rod. At suitable intervals along the rocking rod 18, one or more locking members 20 is 60 fixed, said members each having a hook-like form as shown in Figs. 3 to 7 inclusive, and being so shaped and arranged as to engage with members fixed upon the opposite edge 65 of the trunk to draw the trunk sections together. Because of space limitations, and the scale of the drawings, only one locking member is shown. In this instance the opposite trunk section 11 is provided with a metallic 70 strap 21 secured on the inside of the trunk and extending at right angles to the edge and projecting across said edge as shown in Fig. 3, being provided with an eye 22 so located 75 that the corresponding hook-like locking member 20 will engage with the eye of the strap when the trunk sections are separated as much as 1 in. or more, whereby the trunk sections may be brought together as the locking member is rocked. The eye 22 is so located 80 and shaped and the hook-like member 20 is so formed that the outer edge of the hook-like member will engage with the strap 21 when rocked from the full line position of Fig. 3 to the dotted line position, thereby 85 forcing the trunk sections apart.

A drawback of trunk locks of the described type has been the difficulty of bringing together and separating the trunk sections when the edges are not precisely parallel, whether 90 arising from injury to the trunk or to play in the trunk hinges or to unevenness of the surface on which the trunk is standing. If the trunk edges are not precisely parallel, when drawn together they will meet at a point and 100 complete closing may then be effected only by striking one of the trunk edges near the point where closing is obstructed. Furthermore, the mechanical connections translating the movement of the hasp into movement of the auxiliary locking devices have frequently 105 been such that considerable force must be used to close and open the trunk. According

to my invention, the auxiliary locks are operated at a considerable mechanical advantage, and the parts are so arranged that at the time when the greatest resistance to relative movement of the sections is encountered, the hasp-controlled linkage is mechanically most effective to exert the greatest force.

In the preferred embodiment there are two arms 23, best shown in Figs. 5, 6 and 7, mounted on the pintle 24 of the hasp hinge and having kerfs 25 for receiving the hasp 14 edge-wise, being held against transverse movement by the hinge, as shown in Figs. 1 and 2. These two arms are thus united with the hasp 15 to turn therewith about the hinge axis and in effect make the hasp a bell crank lever having a short arm and a long arm (the hasp proper), the preferred arrangement affording a mechanical advantage of about 6:1. The rockable rod 18 has an arm 26 secured thereto which swings in a slot 27 provided in and extending transversely of the edge of trunk section 10. The two arms joined to the hasp and the arm 26 connected with the rockable rod 20 are operatively connected by a link 28 which is pivoted to the outer end of arm 26 and pivotally connected to a pin 29 extending between the outer ends of the two arms 23. As will be noted from Figs. 5, 6 and 7, the two arms 23 extend generally at an obtuse angle 30 to the plane of the hasp and the parts are so arranged that when the hasp is about half way closed, as in Fig. 6, the hook-like locking member is about in the position wherein it meets with the greatest resistance when opening or closing a trunk, while the force exerted to cause rocking of the rod 18 is most effective because the link 28 is then about at right angles to the line of force through the link. See also Fig. 7. However, when the trunk 40 is locked, as shown in Fig. 5, the linkage is in such position that again a maximum force may be exerted to open the trunk. When the hasp is in its open position of Fig. 7, further swinging movement is prevented by means of a stop 30 formed on one or more of the hook-like locking devices, said stop also preventing the linkage from assuming a dead center position.

50 A lock constructed as shown and described is inexpensive to manufacture, is strong and serviceable and may be depended upon to close forcibly and to open in like manner the most tightly fitting trunk sections.

55 Obviously the present invention is not restricted to the particular embodiment thereof herein shown and described. Moreover, it is not indispensable that all the features of the invention be used conjointly since they may be employed advantageously in various combinations and sub-combinations as defined in the claims.

What I claim is:

60 1. A trunk lock comprising, in combination, a hinged hasp with a lock at its free end;

a rod arranged parallel to the hinge axis; locking devices secured to the rod; and a linkage connecting the hasp and the rod so that swinging of the hasp rocks the rod and actuates the locking devices; said linkage comprising 70 an arm rigidly secured to the hasp adjacent the hinge and extending at an obtuse angle to the general plane of the hasp, an arm rigidly secured to the rocking rod about in the plane of said hasp-carried arm, and a link 75 pivotally secured to both of said arms near the outer or free ends of each.

2. A trunk lock comprising, in combination, a hinged hasp with a lock at its free end; 80 a rod arranged parallel to the hinge axis; locking devices secured to the rod; and a linkage connecting the hasp and the rod so that swinging of the hasp rocks the rod and actuates the locking devices; said linkage comprising 85 an arm rigidly secured to the hasp adjacent the hinge and extending at an obtuse angle to the general plane of the hasp, an arm rigidly secured to the rocking rod about in the plane of said hasp-carried arm, and a link 90 pivotally secured to both of said arms near the outer or free ends of each; and stop means 95 carried by the rocking rod to limit in one direction the arcuate movement of said locking devices, and to prevent the linkage from assuming a dead-center position.

3. A trunk lock comprising, in combination, a hinged hasp provided with a key lock at its free end; swingable locking devices controlled by swinging of the hasp to draw the edges of the trunk together or force them apart; a rod rockable on its axis and carrying said locking devices; and means interposed between the hasp and rod to rock the same; said means including a short arm split to embrace the hinged end of the hasp and the hinge pintle, and forming with the hasp a bell crank lever for actuation of the locking devices.

4. A trunk lock comprising, in combination, a hasp hinged to the trunk and having 110 a lock at its free end; a rod carried by the trunk parallel to the hinge axis of the hasp and being rockable on its axis; and a linkage connecting the hinged end of the hasp with the rod to effect rocking of the rod 115 through a smaller arc than the arc through which the hasp moves; and hook-like locking devices secured to said rod and movable thereby to force the trunk sections together or to separate them forcibly according to the direction of movement.

5. A trunk lock comprising, in combination, a hasp hinged to the trunk and having 125 a lock at its free end, and swingable in a plane at right angles to the face of the trunk; a rod carried by the trunk near one edge and so mounted as to rock on its axis; locking members secured to the rod to be oscillated thereby; and movement-reduction connections between the hasp and the rod and so 130

- constructed and arranged that a movement of the hasp greater than 90° swings the locking members through arcs less than 90°, to force the trunk sections together or to separate them
- 5 **5** forcibly, according to the direction of movement.
6. A trunk lock comprising, in combination, a hinged hasp; an arm extending from the hinged end of the hasp; a rockable rod
- 10 **10** mounted on the trunk and carrying a locking device; an arm fixed to said rod to facilitate rocking of the same; and means connecting the two arms together so arranged relative thereto that substantially the maximum turning moment is applied to the second named ¹⁵ arm when said locking device offers the greater resistance.

In testimony whereof, I have signed my name to this specification.

BENJAMIN H. ERWIN.
